UNITED STATES PATENT OFFICE.

ROSCOE M. GRIZZLE AND AARON H. THACKER, OF TERRE HAUTE, INDIANA.

TIE.

1,392,146.

Specification of Letters Patent. Patented Sept. 27, 1921.

Application filed March 30, 1921. Serial No. 457,004.

To all whom it may concern:

Be it known that we, ROSCOE M. GRIZZLE and AARON H. THACKER, citizens of the United States, residing at Terre Haute, in 5 the county of Vigo and State of Indiana, have invented new and useful Improvements in Ties, of which the following is a specification.

Our present invention has reference to a 10 metallic tie for railway rails and to means for securing rails on the tie.

Our primary object is to produce a metallic tie which will engage the roadbed in a manner that will prevent either the lateral, 15 longitudinal or sinking movement thereof and which has associated therewith spring influence means for holding the rails thereon, said means permitting a movement of the rails only in a longitudinal direction by 20 the expansion or contraction of the said rails.

A further object is to produce a metallic tie for railway rails in which spring influenced means is employed for locking the 25 rails on the tie, said means being susceptible of longitudinal adjustment and held so adjusted, whereby the rails will be properly gaged and positively held in proper spaced relation with respect to each other.

30 The foregoing, and other objects which will appear as the nature of the invention is better understood, may be accomplished by a construction, combination and operative association of parts, such as is disclosed by 35 the drawings which accompany and which form part of this specification.

In the drawings:—

Figure 1 is a plan view showing rails supported on and secured to ties in accordance 40 with this invention.

Fig. 2 is a sectional view on the line 2—2 of Fig. 1.

Fig. 3 is a transverse sectional view on the line 3—3 of Fig. 2.

45 Fig. 4 is a similar section on the line 4—4 of Fig. 2.

Fig. 5 is a similar section on the line 5—5 of Fig. 2.

50 Fig. 6 is a fragmentary perspective view looking toward the headed end of the shank portion of one of the rail engaging members.

Fig. 7 is an enlarged fragmentary plan view showing the manner in which the rails may be adjusted on the tie.

55 Fig. 8 is a sectional view on the line 8—8 of Fig. 7.

Fig. 9 is an elevation of the push bar employed in the adjusting means.

Fig. 10 is a similar view of the pull bar employed.

60 Fig. 11 is an elevation of the lower portion of the operating lever for the adjusting means.

As disclosed by the drawings, the body of our improved metallic tie comprises a substantially rectangular box-like member which is broadly indicated by the numeral 1. The tie 1 has an open top, its lower longitudinal edges formed with outwardly inclined flanges 2, and its lower end corners likewise formed with outwardly inclined flanges 3. The flanges 2 and 3 are designed to enter the roadbed, and when the said roadbed is tamped around the tie, these flanges will hold the tie against longitudinal, lateral or 75 sinking movement.

The tie, at a suitable distance from the ends thereof is integrally formed with transverse partitions 4 and the center of the tie has its inner walls formed with oppositely arranged lugs 5 that are slotted from their upper ends, as indicated by the numeral 5'.

The bottom of the tie, outward of the partitions 4 has integrally formed thereon substantially U-shaped stirrups 6.

The top of the tie is designed to be covered by hingedly connected plates 7—7 which, however, are not of a length to fully cover the tie, the said plates 7 having depressed portions 8 at the outer ends thereof which enter the tie, and over the lips formed by the said depressed portions the base flanges of the rails 9 rest, the said rails also resting on opposite ends of the upper edges 90 of the tie. Resting on the tie, outwardly of the rails 9 are plates 10.

The outer longitudinal edges of the base flanges of the rails are engaged by hooks 11 formed on the angle ends 11' of rods or shanks 12. The hooks 11 pass through suitable openings in the plates 10, the said plates being provided with upstanding lugs 13 to the sides of the openings, and a pivot 14 passes through the lugs and through the hook. This, in addition to holding the hooks in proper rail engaging position, may also serve for retaining the plates 10 on the tie.

105 The rods or shanks 12 pass through suitable openings in the respective partitions 4. 110 The rods or shanks are round in cross section and have their free ends provided with re-

duced extensions in the nature of necks 15 that terminate in ball heads 16. The shanks, inward of the neck portions 15, are provided with a plurality of spaced circumferentially disposed angularly arranged slots 17 one of which having passed therethrough a key 18. The key has corner extensions in the nature of bits 19, the slots 17 being of a length to receive therethrough the said extensions or bits of the key, and the bit portions of the key are forced over the opposed faces of the shank when the key is influenced by the engagement of a follower plate 20 that is arranged on the shank 12 and that is influenced by a spring 21 which surrounds the shank and exerts a pressure between the partition 4 and the said follower plate. In this manner, the hooks 11 are retained under spring tension, and the tension of the springs 21 may be adjusted by arranging the key 18 in the proper slot 17 in the shanks 12.

The inner longitudinal edges of the base flanges of the rails are engaged by the hooked ends 22 of members 23 that have their body portions provided with openings through which the respective shanks 12 freely pass, and their lower ends formed with hooks 24 that engage the respective

stirrups 6 of the tie.

Surrounding the shanks 12 and exerting a pressure between the partitions 4 and the members 23 are springs 25. In this manner, it will be noted that the rail engaging members for the respective rails are spring influenced in opposite directions, the said springs forcing the said members into tight engagement with the base flanges of the respective rails, the hooked upper ends of the members 23 passing through suitable slots 26 in the lipped ends 8 of the hinged cover plates 7.

When it is desired to adjust the tension of the springs, or when it is desired to arrange the rails at a determined or proper gage on the tie, the hinged plates 7 are removed. It should have been stated that the knuckles of the hinges which connect the plates 7 are received in the depressions 5' of the lugs or bosses 5 which, in addition to the manner in which the lips 8 of the said plates underlie the rails and the walls of the slot 26 in the said lips are contacted by the opposed faces of the hooked upper end of the member 23, holds the said hinged plates on the tie. In the notches 5' we arrange the trunnioned ends 27 of a cross sectionally squared shaft 28. On the shaft there is eccentrically mounted a pair of disks 29 respectively, the said disks being surrounded by ring heads 30 formed on one end of bars 31. The opposite ends of the bars are offset angularly, as at 32 and provided each with an extending lip 34. The outer shoulders provided by the portions 32

of the bars 31 contact with the inner faces of one of the follower plates 20, while the lips 32 rest on the upper edge of the said plate. Centrally on the shaft 28, between the disks 29 there is eccentrically mounted another disk 35. The major portion of this disk, with respect to the squared opening 36 therein is projected oppositely from the major portion of the disks 29 with respect to their squared openings 37 that receive the shaft 28 therethrough. Surrounding the disk 35 is a ring head 38 formed on one end of a bar 39, the opposite end of the bar being hook-shaped, as at 40 and being bifurcated, as at 41. The bifurcated portion of the hook is designed to receive therein the reduced neck 15 on the shank 12, the ball head being received in the concaved inner face of the hook 40. On the shaft 28, to one side of the pull bar 39 there is removably secured the headed end 41 of a lever 42. It will be apparent that by swinging the lever in one direction, the eccentrically mounted disks will be revolved with the shaft 28, influencing the ring heads 30 and 38 of the respective bars 31 and 39, causing the bars 31 to exert a pushing pressure against the follower plate and the hooked end 40 of the bar 39 to exert a pull in a direction toward the center of the tie on the shank 12 of the hook 11. When proper adjustments have been made, the key is inserted in one of the slots or notches in the shank, both of the springs being sustained under tension which will effectively hold the rails in proper position on the ties. The adjusting means is then removed, and the hinged plates are again arranged to cover the open top of the tie.

It is thought that the foregoing description, when taken in connection with the drawings will fully set forth the construction and advantages of the improvement to those skilled in the art to which such inventions relate, but it is to be also understood that the nature of the invention is such as to render the same susceptible of changes in size, proportion, etc., and therefore the improvement is only limited to the scope of the attached claims.

Having described the invention, we claim:

1. In a device for the purpose set forth, a metallic tie and rails resting thereon, clamps carried by the tie for holding the rails on said tie, said clamps including respectively a longitudinally disposed member having a hooked end for engaging the outer flange of the rail, and a swinging member having a hooked end for engaging the inner edge of the rail, and independent spring means influencing each member for holding the same in rail engaging position.

2. In a device for the purpose set forth, a metallic tie, and rails resting on the tie,

clamps carried by the tie and engaging the base flanges of the rails, independent spring means influencing the clamps in rail engaging direction, and means inclosing said 5 spring means and partially inclosing the clamps.

3. In a device for the purpose set forth, a metallic tie having an open top, and rails resting on the tie, hinged covers closing the 10 top of the tie and having portions disposed below the rails, clamps having their body portions arranged in the tie and having hooked heads projecting through the cover and engaging the base flanges of the rail, 15 spring means guided on the outer clamps for moving the inner clamps to rail engaging position, and means influencing the outer clamps for bringing the same to rail engaging position.

20 4. In a device for the purpose set forth, a metallic tie having an open top, and rails resting on the tie, hinged covers closing the top of the tie and having portions disposed below the rails, clamps having their body 25 portions arranged in the tie and having hooked heads projecting through the cover and engaging the base flanges of the rail, spring means guided on the outer clamps for moving the inner clamps to rail engaging 30 position, and means influencing the outer clamps for bringing the same to rail engaging position, and means for adjusting the rails on the ties and for regulating the tension of the spring means which influence the 35 clamps.

5. In a device for the purpose set forth, a metallic tie having an open top, hinged closures for the top having depressed portions arranged below the rails, oppositely disposed longitudinally extending rods supported by guides in the tie and having hooked ends which pass through the closures for engaging the outer base flanges of the rails, inner clamps hingedly supported on 40 the bottom of the tie and having upper hook-shaped ends passing through the covers and engaging the inner flanges of the rails, spring means surrounding the rods exerting a pressure between the guides for the rods 45 and said inner clamps for forcing the latter to rail engaging position, spring means surrounding the rods and also contacting with the guides for the rods, adjustable means 50

on the rod engaging said spring means and whereby the hooked ends of the rods are 55 forced to rail engaging position.

6. In a device for the purpose set forth, a metallic tie having an open top, hinged closures for the top having depressed portions arranged below the rails, oppositely disposed longitudinally extending rods supported by guides in the tie and having hooked ends which pass through the closures for engaging the outer base flanges of the rails, inner clamps hingedly supported on 60 the bottom of the tie and having upper hook-shaped ends passing through the covers and engaging the inner flanges of the rails, spring means surrounding the rods exerting a pressure between the guides for the rods 65 and said inner clamps for forcing the latter to rail engaging position, spring means surrounding the rods and also contacting with the guides for the rods, adjustable means 70 on the rod engaging said spring means and 75 whereby the hooked ends of the rods are forced to rail engaging position.

7. In a device for the purpose set forth, a hollow metallic tie having an open top, and rails resting on the tie, said tie having inner 80 transverse partitions, hinged closures for the top of the tie having depressed portions disposed beneath the rails, oppositely directed rods guided through the respective partitions, hooks on the outer ends thereof 85 for engaging the outer base flanges of the rails, stirrups in the tie adjacent each partition, members having inner hooked ends to engage the stirrups and upper hooked ends passing through the closures for engaging 90 the inner base flanges of the rails, spring means surrounding the rods and exerting a pressure between the partitions and the last mentioned members, a follower plate on each 95 of the rods, means adjustably holding the plate on the rod, spring means on each rod between each follower plate and the respective partitions, and means for collectively influencing the rail engaging members to 100 gage the rails on the tie and for adjusting the tension of the spring means which influence the rail engaging members.

In testimony whereof we affix our signatures.

ROSCOE M. GRIZZLE.
AARON H. THACKER.
